UNITED STATES PATENT OFFICE.

JAMES A. MCNAMEE, OF CAMBRIDGE, MASSACHUSETTS.

FIREPROOF FLOORING.

SPECIFICATION forming part of Letters Patent No. 669,801, dated March 12, 1901.

Application filed January 12, 1901. Serial No. 43,034. (No model.)

To all whom it may concern:

Be it known that I, JAMES A. MCNAMEE, a citizen of the United States, residing at Cambridge, in the county of Middlesex and State 5 of Massachusetts, have invented new and useful Improvements in Fireproof Floorings, of which the following is a specification.

This invention relates to improvements in fireproof flooring in buildings; and it is carried out as follows, reference being had to the accompanying drawings, wherein—

Figure 1 represents a top plan view of the invention, showing the metal bands or wires secured to the clips on the I-beams before 15 being embedded in the concrete or plastic material. Fig. 2 represents a cross-section on the line 2 2 in Fig. 1, showing the said metal bands or wires embedded in the concrete or plastic material. Fig. 3 represents an enlarged top plan view of one of the I-beams and clips ready to receive the metal bands or wires. Fig. 4 represents a cross-section on the line 4 4 in Fig. 3, showing the bands or wires connected to said clips. Fig. 5 represents a detail top plan view of one of the 25 clips, and Fig. 6 represents a cross-section on the line 6 6 shown in Fig. 5.

Similar letters refer to similar parts wherever they occur on the different parts of the 30 drawings.

In the drawings, A A represent the usual metal I floor-beams employed in fireproof floorings. To the opposite edges of the upper flanges of said metal I-beams I attach the 35 metal clips B B, each one having at its outer end a hook b, adapted to be hooked onto the upper flange of the I-beam, as shown. The free ends of said clips are provided with side recesses or notches b' b'', as shown.

CC are metal bands or wires, the ends of 40 which may be attached to the walls of the building in any suitable or convenient manner, such wall-connecting device being, however, not shown in the drawings, as it does 45 not form an essential part of my invention.

The metal bands or wires C are placed in and interlocked with the side notches b' b'', as shown in the drawings, and looped between the floor-supporting I-beams, as shown in 50 Figs. 1 and 2.

In practice I prefer to attach at intervals

to the metal bands or wires C C the transverse metal bands or wires D D, as shown in Figs. 1 and 2, so as to hold the metal bands or wires C C at proper distances apart. After the said 55 metal bands or wires C C (with or without the transverse bands or wires D D) have been placed in position and interlocked with the clips B B on the metal I-beams A A, as shown, I place beneath the lower flanges of said I-beams suitable temporary boards E E (shown in dotted lines in Fig. 2) and fill the spaces between the I-beams with suitable concrete or plastic material F F, in which the metal bands or wires C C are caused to be embedded, 60 as shown, and after said plastic material is set and hardened I remove the supporting boards E, thus causing the plastic fireproof mass F to be supported on the metal bands or wires C C, and as the latter are attached 65 by means of the clips B B to the individual I-beams in the series it will be seen that any sagging of the mass of plastic material between the I-beams is entirely prevented, thus making a very strong and durable fireproof 70 flooring. After the flooring has thus been made I place on top of it the usual wooden floor-boards, which are, however, not shown in the drawings.

By the use of the notched and hooked metal 80 clips B B, I am enabled to build up the flooring in a very simple, rapid, and strong manner, and by the use of said clips I may readily arrange the supporting bands or wires C C nearer or farther apart, as circumstances may 85 require. A fireproof flooring thus constructed can be made by unskilled labor in a very quick manner, as all that is needed to do is to place the notched metal clips B B onto the opposite upper flanges of the I-beams and interlock the looped metal bands or wires C C with the notches in the said metal clips previous to filling the spaces between the I-beams with the plastic material, which is thus caused to be supported on said looped metal bands 90 or wires, for the purpose stated.

What I wish to secure by Letters Patent and claim is—

The herein-described fireproof flooring, consisting of parallel metal I-beams A, A, combined with hooked metal clips B, B, adapted 100 to be hooked and attached to the upper oppo-

site edges of the I-beams, and having side notches b' , b'' , adapted to receive a series of looped lateral metal bands or wires C, C, embedded within a mass of concrete or plastic material substantially as and for the purpose set forth.

5 In testimony whereof I have hereunto set

my hand in presence of two subscribing witnesses.

JAMES A. McNAMEE.
